UNITED STATES PATENT OFFICE.

EDMOND J. TOAL, OF MINNEAPOLIS, MINNESOTA.

WRITING TABLET.

Application filed February 20, 1922. Serial No. 537,916.

To all whom it may concern:

Be it known that EDMOND J. TOAL, a citizen of the United States, residing at Minneapolis, in the county of Hennepin, State of Minnesota, has invented a new and useful Writing Tablet, of which the following is a specification.

The present invention is a stationery article and relates particularly to such devices known as scratch pad holders and designed for desk use in offices, stores and the like.

The object of the invention is the production of an inexpensive and simply constructed stationery article of the above stated character, in which rolls of paper are used and which device is highly useful.

The essential features of the invention reside in a pocket formed, preferably, in the rear end of a body member or base and of such shape and size as to have a roll of paper rest and be retained therein, the forward portion of the base providing a smooth tablet or writing surface over which a portion of the paper is drawn from the roll. The tablet portion of the device is provided with guides for maintaining in position the paper drawn thereover, and other means are provided for preventing the roll of paper from moving out of said pocket while the paper is being drawn from the roll. One of said guides acts as a cutting edge permitting lengths of paper from the roll, which have been written upon, to be torn off.

With the above and other objects in view the invention resides in the sundry details of construction, combination and arrangement of parts hereinafter more fully described.

In this specification and the annexed drawings, the invention is disclosed in the form in which it is considered to be the best, but the invention is not limited to such form because it is capable of being embodied in other forms; and it is to be understood that in and by the claims following the description herein it is intended to cover the invention in whatever form it may embody within the scope thereof.

In the drawings which disclose the preferred embodiment of the invention as at present devised:

Figure 1 is a perspective view of the scratch pad stationery device forming the present invention,

Figure 2 is a longitudinal sectional view taken through the device and illustrating the manner in which a roll of paper is received and maintained in position thereon, and how the paper is threaded through said roll over the tablet portion of the base,

Figure 3 is a perspective view of the rear guide provided with an upstanding flange which acts to maintain the roll of paper in position on the pocket of the base, as the paper is being drawn from the roll over the tablet portion thereof, and

Figure 4 is a perspective view of another form of guide for the paper.

Referring particularly to the drawings the invention consists of a body member or base 1, preferably rectangular, and made of wood, metal or any suitable material, and finished in an ornamental manner to be used on office desks and the like. This base has its upper face inclined from its rear end towards its front end, in the manner shown in the drawings, but this is not essential to the invention.

The upper surface of the base has provided thereon at its rear end portion a recess or pocket 2 having, preferably, a rounding or concaved bottom wall *a* and side walls *b*. The pocket 2 is designed to receive a roll of paper 10 which is adapted to rest and be supported on the concave wall *a* of the pocket of the base.

The portion of the base 1 lying forwardly of the pocket 2 provides a smooth tablet surface, preferably rearwardly inclined, to provide a convenient writing surface 4 over which the strip of paper 5 from the roll 3 is drawn.

The strip 5 of paper drawn over the tablet 4 from the roll 3 is held in position and guided during its movement by the guides 6 and 7. These guides consist, preferably, of strips of metal, or other material, extending transversely across the end portions, respectively, of the tablet 4 and are spaced over the surface thereof, the end portions of the guides being bent at right angles to their body portions and secured in position on the base with any suitable means, such as, for instance, by the screws 8. The guide 6, at the front end of the base, has a cutting edge 9 whereby a length of paper, which has been written upon, may be torn off at convenient and desired lengths for such purposes as may be desired.

The guide 7 is positioned adjacent the

forward edge of the pocket 2 and is, preferably, provided with an upstanding rearwardly inclined flange 10, this flange serving as a guard to engage the roll of paper 5 at a point above its axis of rotation and to prevent the roll from jumping out of the pocket due to any unusual pull or jerk upon the strip of paper 5, while being unwound from the roll 3. It will be observed that the roll 3 is not journaled in the pocket 2 but merely rests therein. This flange 10 also serves as a convenient means for advertising or for containing such other information as may be desired. It is to be understood, however, that in practicing the present invention, the flange 10 may be omitted, but its provision is regarded as desirable and advantageous.

The memorandum pad of this invention is an article of stationary and is adapted for desk use in offices, stores and the like, and is, therefore, provided with cushion supporting feet 11 of felt, rubber or other suitable material, for preventing scratching or marring of furniture upon which it is placed.

As can be readily observed from the above, the roll of paper used in the present invention is, preferably, of such width as to occupy the entire pocket 2 and is threaded under the guides 7 and 6, respectively. As the paper is written upon on the tablet portion 4, the strip 5 is drawn through the guides unwinding the roll 3, said roll holding its position in the pocket 2 because of its weight and the particular formation of said pocket as well as the provision of the flange 10.

Having thus described my invention and what I claim and desire to secure by Letters Patent is:

1. A writing tablet comprising a base member having its upper surface cut away to form a recess in which a roll of paper may rest, a tablet portion on the upper surface of said base member adjacent said re-

cess and over which a strip of paper from said roll may be drawn, and means for guiding the strip from the roll over said tablet portion.

2. A writing tablet comprising a base member having a concave depression on its upper surface at the rear end portion thereof, a tablet portion on the upper surface of said base lying forwardly of said recess toward the other end of said base, said depression forming a pocket in which a roll of paper may rest, and guides for guiding a strip of paper from said roll over said tablet portion when said strip is drawn from said roll.

3. A writing tablet comprising a base having an inclined upper surface, an open faced chamber on said upper surface of the base at its higher end portion to receive a roll of paper therein and to retain said roll when a strip is drawn from said roll, a tablet portion provided by said inclined upper surface and between said chamber and the lower end of said surface, and guide strips extending transversely across said tablet portion at a point adjacent the edge of said chamber and said lower end of said upper surface, said strips being spaced from said surface whereby the paper of the roll may be threaded under said guides and maintained in position on said tablet portion of the base.

4. In a writing tablet, a base member having a surface thereof formed with a depression providing a pocket in which a roll of paper may rest, means for guiding a strip of paper from the roll over said surface of the base, an upwardly extending flange adjacent said pocket to prevent said roll of paper from accidental removal from said pocket when a strip of paper is drawn from said roll over said surface while the roll rests in said pocket.

In testimony whereof I have hereunto set my hand.

EDMOND J. TOAL.
